(57) **CLAIM**

The ornamental design for a rotating laser, as shown and described.

DESCRIPTION

FIG. 1 is a perspective view of a new design for a rotating laser according to our invention illustrating the front and right view thereof;

FIG. 2 is a top view thereof;

FIG. 3 is a front view thereof;

FIG. 4 is a right view thereof;

FIG. 5 is another perspective view illustrating the right and rear view thereof; and,

FIG. 6 is a left view thereof.
